Primary Examiner — Susan Moon Lee(74) *Attorney, Agent, or Firm* — Leydig, Voit & Mayer, Ltd.(57) **CLAIM**

I claim the ornamental design for an optical transmission-conversion device for producing a magnified image, as shown and described.

DESCRIPTION

FIG. 1 is a front perspective view of an optical transmission-conversion device for producing a magnified image according to the present invention;

FIG. 2 is an exploded perspective view of the optical transmission-conversion device for producing a magnified image in which the viewer is detached from the stand;

FIG. 3 is a top view of the optical transmission-conversion device for producing a magnified image;

FIG. 4 is a side perspective view thereof;

FIG. 5 is a rear view thereof;

FIG. 6 is a bottom view thereof; and,

FIG. 7 is an exploded perspective bottom view of the optical transmission-conversion device for producing a magnified image in which the viewer is detached from the stand.

Broken lines and unshaded portions contained within broken line are not claimed.

1 Claim, 7 Drawing Sheets(56)
